UNITED STATES PATENT OFFICE.

HENRY C. WEEDEN, OF BOSTON, MASSACHUSETTS.

WASH-BASIN.

SPECIFICATION forming part of Letters Patent No. 440,211, dated November 11, 1890.

Application filed June 27, 1890. Serial No. 356,945. (No model.)

To all whom it may concern:

Be it known that I, HENRY C. WEEDEN, of Boston, in the county of Suffolk and State of Massachusetts, a citizen of the United States, 5 have invented certain new and useful Improvements in Wash-Basins, of which the following is a specification.

My invention relates to that class of basins known as "set-bowls," intended to be permanently set in place in an apartment in connection with suitable water-supply and waste pipes; and its object is to improve these structures, particularly with regard to the construction of the overflow and waste. 15 Such bowls have heretofore been made with a recess in the rear, in which the discharge-orifice of the basin has been located. The overflow most commonly adopted heretofore has been a stand-pipe formed at the lower 20 part to act as a plug or stopper to the discharge-orifice, and open at its upper part, so that when the basin is filled above a certain line it will overflow through the stand-pipe. It will be obvious that with a stand-pipe overflow so constructed it is necessary 25 that it should be moved when it is desired to empty the basin, and this feature of making the overflow stand-pipe a moving part has been found in practice to be disadvantageous. 30

The object of my improvement is to provide a bowl wherein the overflow-pipe shall be a siphon integrally and immovably a portion of the bowl-wall, so that the whole can 35 be constructed of a single integral piece of earthenware, that being the material now preferred for such devices.

In the accompanying drawings, Figure 1 represents in top plan, and Fig. 2 in vertical 40 section, a bowl embodying my present improvement, which I will now proceed to describe.

The main portion A of the bowl may be made square or oval, as desired. In the center of the rear wall is provided the recess B, at the bottom of which is located the discharge-orifice C. In the recessed portion of the wall of the bowl I construct a siphon-formed overflow-passage D E, the short leg

D of which communicates with the bowl, 50 preferably at a point d, at or near its bottom level. The long leg E of the siphon discharges into the outlet portion F of the bowl. The orifice C is adapted and intended to be closed by means of a basin-plug H of 55 ordinary construction. For the convenient reception of the plug, and also to make a convenient union with the discharge-pipe leading from the bowl-outlet, a shell I may be inserted in the outlet F, as shown. The upper portion of this shell receives the plug H, and the shell is slotted, as at i i, so that water discharged from the siphon D E may pass off, even though the plug H be seated.

It will be seen that the device above described 65 may be constructed of a single integral piece of earthenware, that it has no moving parts, and consequently that it is entirely free from the liability to derangement that always exists in these devices when moving 70 parts are employed.

The discharge-pipe G of the bowl is provided with a trap J, preferably of the S form, as shown, to cut off the passage of noxious vapors from the soil-pipe. From some 75 point in the outlet above this trap I lead up to a point above the bend of the siphon-overflow an air-pipe K. This air-pipe serves to prevent the apparatus from becoming air-bound, which might be the case if the outlet 80 were omitted.

The operation of the device is very simple. If the discharge-orifice be closed by the plug, water may be admitted into and retained by the bowl until it reaches the height 85 of the bend of the siphon overflow-pipe D E, thus enabling an ample depth of water to be had in the bowl when in use. At the same time, should water be allowed to enter the bowl to a greater height, the siphon action 90 of the overflow is started, and the contents are thus removed rapidly and effectually.

I make no claim, broadly, to the idea of a siphon-formed overflow-pipe, as such is not 95 new with me.

I claim—

The improved bowl and overflow herein

described, having the main portion A, rearwardly-located recess B, siphon-formed over-flow-pipe D E, and discharge-pipe G, a trap J, and air-pipe K, leading from the said discharge-pipe to a point above the bend of the said siphon-formed overflow, substantially as set forth.

In testimony whereof I have hereunto subscribed my name this 6th day of June, A. D. 1890.

HENRY C. WEEDEN.
